RECTIFICATION COLUMN

Cornelius Otto Jonkers, Jacob Willem Laurens Köhler, and Johannes van der Ster, Eindhoven, Netherlands, assignors, by mesne assignments, to North American Philips Company, Inc., New York, N. Y., a corporation of Delaware

Application June 17, 1954, Serial No. 437,456

Claims priority, application Netherlands June 18, 1953

14 Claims. (Cl. 62—122)

The invention relates to a rectification column for separating gaseous mixtures, this column comprising a boiling vessel for the fraction having the highest boiling point, to which boiling vessel heat is supplied by means of a heat exchanger which also withdraws heat from the gaseous mixture to be fractionated. The rectification column has the feature that the heat exchanger comprises a part which is located in the boiling vessel and by means of which heat is supplied to the fraction having the highest boiling point and a further part which is located outside the boiling vessel and which is in thermal contact with the gaseous mixture to be fractionated, these parts being in thermal contact with one another by way of a support.

The heat exchanger hitherto frequently used in rectification columns comprises, in general, a tube located in the boiling vessel through which the gaseous mixture to be fractionated is conducted. In such cases it will be necessary to eliminate from the medium any contaminations liable to separate out during cooling of the medium, before the mixture is supplied to the heat exchanger, since, if these contaminations were separated out in the heat exchanger, the heat exchanger could be clogged comparatively soon. Cleaning of such a heat exchanger located in the boiling vessel gives rise to comparatively great difficulties.

In the heat exchanger according to the invention any impurities will settle in the part located outside the boiling vessel, so that any cleaning may be carried out in a simpler manner.

In a preferred embodiment of the invention the part of the support located outside the boiling vessel extends transversely to that wall of the boiling vessel which constitutes the partition between the two parts of the heat exchanger. In a further embodiment of the invention the part of the support outside the boiling vessel is provided with a plurality of extensions with which the gaseous mixture to be fractionated is in thermal contact, the heat of the extensions being conducted away for at least 20% by conduction through the support to the part of the heat exchanger inside the boiling vessel.

Consequently, the heat exchanger according to the invention, used in a rectification column, may be utilised successfully as an ice separator. In this case, it will in general be necessary to purify the medium prior to its supply to the heat exchanger, for example by conducting it through chemical substances binding the impurities. The rectification column according to the invention is then characterized in that a gaseous mixture to be fractionated is conducted through the part of the heat exchanger located outside the boiling vessel, in which one or more components are separated out by cooling, this (these) component(s) precipitating on at least one of the extensions of this part, so that in the proximity of these extensions the composition of the medium is varied and the temperature at which the component(s) can separate out, decreases, whilst by suitable choice of the structural parts of the heat exchanger the mean temperature of each of these extensions, viewed from the hot side

2

of the heat exchanger, is at the most 20° C., preferably at the most 10° C. higher than that of the next following extension and in normal operation of the heat exchanger the mean temperature of the extension at which the separation starts is at the most 20° C., preferably at the most 10° C. lower than the point of separation of that component of the medium as it is supplied to the extensions. It has been found to be desirable to decrease gradually the temperature of the medium to be cooled, whilst the medium is to be brought into turbulence in a manner such that all particles of the medium contact as frequently as possible with the walls of the heat exchanger. If this were not the case, ice particles could already be formed in the gas, consequently before the medium has come into contact with the extensions; it is difficult for the ice separator to collect all these ice particles, which are carried along by the medium.

In the heat exchanger described above only after a comparatively long time such a quantity of solid substance will have been separated out on the extensions that it is necessary to remove it. This may for example be carried out by heating the heat exchanger so that the solid substance will be volatilized or become liquid. In order to cause the extensions of the support section lying outside the boiling vessel to adopt the required temperature, the support in a further embodiment of the invention has parts of different heat resistance. The heat exchanger according to the invention may be used not only for freezing out impurities but also for further cooling of the medium from which the component(s) has (have) been separated. For this purpose the heat exchanger has the feature that the support section lying outside the boiling vessel is provided with a plurality of extensions, on which the component(s) separate out and with a plurality of extensions by means of which the medium, from which the component(s) has (have) been separated is further cooled.

In a further embodiment of the invention the part of the support located outside the boiling vessel is provided with at least two groups of extensions, serving for separating out one or more components for the case in which the said part of the heat exchanger is traversed by a gaseous mixture containing a plurality of components to be separated and having different separation ranges; at one group of extensions mainly the component(s) of one separation range and at the other group of extensions mainly the component(s) of the other separation range is (are) separated out. The extensions of one group have in succession a temperature difference of not more than 20° C., preferably not more than 10° C.

Since, in general, between the separation ranges a comparatively great temperature difference will prevail, it is advantageous, in accordance with a further feature of the invention to provide between the two groups of extensions a further group of extensions, serving mainly for cooling the medium. With this further group of extensions the aforesaid temperature differences between the extensions need not be taken into account, since no ice or only a small quantity of ice will be separated out at these extensions. For the same reason the extensions may be arranged comparatively close to one another, so that this section will occupy comparatively little space. According to a further feature of the invention the extensions of the various groups are arranged in close rows behind one another. Thus the temperatures of the heat exchanger vary little with the quantity of medium passing through it.

The desired temperatures of the extensions may be obtained by constructing the support in a manner such that its parts have the required heat resistances. This heat resistance may be obtained by providing the desired dimensions, for example thicknesses or lengths for the

support or by constructing the support from a special material. However, as an alternative in a further embodiment of the invention, at least some of the extensions may have relatively different heat resistances. In this case the heat resistance of the support need not fulfil particular requirements.

The heat exchanger may be constructed in various ways. In one embodiment of the invention the part of the support located outside the boiling vessel is provided with extensions, constructed in the form of transverse partitions, bounding spaces between the hot side of the heat exchanger and the cold side thereof, these spaces communicating with one another through apertures, so that the medium can flow through these apertures from the spaces of the hot side of the exchanger to the cold side thereof. In this embodiment it is desirable for the apertures to be such that the medium traversing this part of the heat exchanger is set turbulent, so that the medium contacts frequently and intensively with the extensions.

The desired turbulence may be obtained by providing the part of the heat exchanger outside the boiling vessel with a wall at a certain distance from the support, the support being provided with extensions in the form of transverse partitions apertures being left, between these partitions and the wall.

In a further advantageous embodiment of the invention that part of the heat exchanger which is located outside the boiling vessel is constituted by a support and a wall spaced apart therefrom by a certain distance, the support being provided with transverse partitions extending up to the wall, apertures being provided in these transverse partitions. In a further embodiment of the invention the apertures in each transverse partition are preferably located at least partly opposite a wall portion of the adjacent transverse partitions. In this manner, in particular, an intensive turbulence of the medium is ensured.

In a further embodiment of the invention the part of the heat exchanger located outside the boiling vessel is also in thermal contact with at least one of the vapour fractions conducted away from the rectification column. This may for example be the fraction having the lowest boiling point.

If the column is used for producing nitrogen, at least part of the vapour fraction conducted away from the column having the highest boiling point will, in accordance with one embodiment of the invention, be in thermal contact with the part of the heat exchanger located outside the boiling vessel.

A structurally simple system is obtained, if in accordance with a further embodiment of the invention, the support is constituted by a tube open at both ends and taken through the bottom of the boiling vessel, that end of the tube which is located in the boiling vessel projecting over the normal liquid level.

In order that the invention may be readily carried into effect, it will now be described with reference to the accompanying drawing, which shows diagrammatically a few embodiments.

Figs. 1 and 2 show a gas fractionating system, provided with a rectification column.

Fig. 2 is a cross-sectional view taken on the line II-II of Fig. 1.

Fig. 3 shows part of the heat exchanger used with the rectification column, the support thereof being surrounded by a wall, apertures being left between the extensions and the wall.

In the embodiment shown in Fig. 4 a few of the extensions of this heat exchanger have different heat resistances.

The system shown in Fig. 1 comprises a rectification column 1; this column has a filling 2 of for example so-called "Raschig" rings. At the bottom the column is provided with a boiling vessel 3, containing a quantity of

the fraction having the highest boiling point in the liquid state. The boiling vessel 3 has a bottom 4, through which a tubular support 5 is taken. This support is secured in thermally conductive manner to the bottom of the boiling vessel. The support has wall portions 6, 7 and 8 of different thicknesses and both on the inner side and on the outer side the support is provided with extensions, for example vanes. The inner side is provided with extensions 9, provided with apertures 10 and 11, as is evident from Fig. 2. The outside of the wall portion 6 of the support is provided with extensions 12; the wall portion 7 has the extensions 13 and the wall portion 8 has the extensions 14. All these extensions are provided with apertures 15, which are in staggered positions in successive extensions. The bottom of the boiling vessel is provided with extensions arranged concentrically about the support 16. The support 5 communicates at the lower side with a duct 17 and on the top side the support extends in the boiling vessel to such an extent that it projects over the normal liquid level in this vessel. The part of the support located outside the boiling vessel is surrounded by a wall 18, having heat-insulating properties. This wall is provided with two supply ports 19, communicating with a duct 20 and with an exit port 21, communicating with a duct 22, which communicates with the gas fractionating portion of the column. The duct 20 comprises a pump 23.

At the top the column communicates through a duct 24 with a cold-gas refrigerator 25, which communicates moreover through a duct 26 with the column. The cold-gas refrigerator has an outlet duct 27 and is driven by an electric motor 28.

The system operates as follows. The medium, for example air to be fractionated is supplied with the aid of the pump 23 through the duct 20 in succession to the spaces between the extensions 14, 13 and 12. Owing to the frequent contact of the medium with the extensions 14 the water vapour contained in the air is frozen out on these extensions. The separation range extends to about -60°C . At the extensions 13 the temperature of the medium is further decreased to about -140°C . and in the part 12 the air is cooled from -140°C . to for example -182°C . The carbon acid then precipitates on the extensions 12. The extensions of the parts 14 and 12 are spaced apart by a comparatively great distance and between the successive extensions of each group prevails a comparatively small temperature difference of for example 8°C . This temperature difference is obtained by constructing the support from parts having different heat resistances.

The air which is purified and the temperature of which is decreased is supplied through the duct 22 to the column 1. This column is constructed, for example in the form of a so-called single column and operates under atmospheric or substantially atmospheric pressure. In the column the air is fractionated. In the boiling vessel 3 of the column is produced a substantially constant quantity of the liquid fraction having the highest boiling point, in this case oxygen. Liquid oxygen flows from the column and evaporates in the boiling vessel. Part of the vapour rises upwards in the column and a further part is conducted away through the tubular support 5 and the duct 17. Inside the support 5 the latter part of the vaporous oxygen is in thermal contact with the air to be fractionated rising upwards outside the support. In this embodiment about 70% of the cold withdrawn from the air will serve to heat this oxygen, whilst 30% is supplied through the support to the oxygen in the boiling vessel, the oxygen thus evaporating.

In the upper part of the column the fraction having the lowest boiling point, in this case, the nitrogen is in the vapour state. The vapour is conducted through the duct 24 to a cold-gas refrigerator 25. By means of the cold produced by this cold-gas refrigerator the nitrogen is condensed and the condensate is supplied, partly as

reflux, through the duct 26 to the column and partly collected through the duct 27. The cold-gas refrigerating machine described above may, as an alternative, be termed a refrigerating machine operating on the reversed hot-gas engine principle. By means of such a machine, described for example in Dutch patent application No. 160,452, very low temperature, for example of -200° C. and even lower temperature may be obtained in one step.

The heat exchanger described above, in which the medium to be cooled and to be fractionated does not traverse the boiling vessel, may be used also with columns of different kind, for example with the so-called double columns.

If the exchanger is filled after some time completely with deposits of impurities, the ice may be removed in a simple manner by scraping after removal of the sheath 18. As an alternative the ice may be removed by heating the heat exchanger.

In the embodiment shown in Fig. 3 the part of the heat exchanger located outside the boiling vessel comprises a support 30, provided with annular extensions 31. These extensions are surrounded by a wall 32, having heat-insulating properties. The extensions 31 do not extend entirely up to the wall 32, so that apertures 33 are left. The medium to be cooled is supplied from below through the port 34 and the cooled medium can be conducted away from below through the duct 35. The support 30 communicates with the boiling vessel of a rectification column. Heat is conducted away from the medium flowing along the extensions through the extensions and the support to this boiling vessel. On the inner side of the support 30 provision is made of vanes 36, with which the gaseous fraction having the highest boiling point and flowing from the boiling vessel is in thermal contact. This heat exchanger operates in a manner completely similar to that of the heat exchanger described above.

Fig. 4 shows a heat exchanger in which the extensions have relatively different heat resistances. In this embodiment a support 40 has constant heat conductivity and the heat exchanger comprises two parts, i. e. part 41 having extensions 42 and part 43 having extensions 44. The part having the extensions 42 serves for separating out a component and the part having the extensions 44 is only used for further cooling of the medium. The extensions 42 and 44 are provided with apertures 45 and 46 respectively and with parts 47 and 48 respectively having each a definite heat resistance. This heat resistance is such that the relative temperature difference of the extensions 42 are comparatively small. The parts 47 and 48 are located in a layer of heat-insulating material applied to the support 40. The extensions are surrounded by a sheath 50 having heat-insulating properties. The medium to be cooled and purified is supplied through the apertures 51 to the heat exchanger and is conducted away through the duct 52.

What is claimed is:

1. A rectification column for separating gaseous mixtures comprising a boiling vessel for the fraction having the highest boiling point, a heat exchanger for supplying heat to the liquid in said boiling vessel from the gaseous mixture to be fractionated, said heat exchanger having a hollow support member, and said heat exchanger being provided with a first part located in said boiling vessel through which heat is supplied to the fraction having the highest boiling point, and a second part including a plurality of extensions extending substantially transversely to the flow of said gaseous mixture located outside of said boiling vessel and in thermal contact with the gaseous mixture to be fractionated, said first and second parts being connected with one another and passing through the bottom of said boiling vessel.

2. A rectification column as set forth in claim 1 further comprising a partition wall separating the first and second parts of said heat exchanger, and said support

member being positioned substantially transversely to said partition wall.

3. A rectification column as set forth in claim 1 wherein said second part includes a plurality of extensions being in thermal contact with the gaseous mixture to be fractionated, and at least 20% of the heat of said extensions being conducted away through said support member to the first part of said heat exchanger.

4. A rectification column for separating gaseous mixtures comprising a boiling vessel for the fraction having the highest boiling point, a heat exchanger for supplying heat to the liquid in said boiling vessel from the gaseous mixture to be fractionated, said heat exchanger having a hollow support member, and said heat exchanger, being provided with a first part located in said boiling vessel through which heat is supplied to the fraction having the highest boiling point, and a second part located outside of said boiling vessel and in thermal contact with the gaseous mixture to be fractionated, said first and second parts being integral with one another and passing through the bottom of said boiling vessel, both the first and second parts of said heat exchanger being provided with extensions, the gaseous mixture to be fractionated being conducted along the extensions of said second part and having at least one of said components being separated out by cooling, the mean temperature of each of said extensions being at the most 20° C. higher than the successive extension as viewed from the hot side of said heat exchanger while in the normal operation of the heat exchanger the mean temperature of one of said extensions is not more than 20° C. lower than the point of separation of said components of the mixture as supplied to said extensions.

5. A rectification column as set forth in claim 4 wherein in the portion of the support member located outside said boiling vessel includes a plurality of parts of different heat resistance.

6. A rectification column for separating gaseous mixtures comprising a boiling vessel for the fraction having the highest boiling point, a heat exchanger for supplying heat to the liquid in said boiling vessel from the gaseous mixture to be fractionated, said heat exchanger having a hollow support member, and said heat exchanger being provided with a first part located in said boiling vessel through which heat is supplied to the fraction having the highest boiling point, and a second part located outside of said boiling vessel and in thermal contact with the gaseous mixture to be fractionated, said first and second parts being integral with one another and passing through the bottom of said boiling vessel, said support member having a portion located outside said boiling vessel being provided with a first plurality of extensions on which at least one of the components of said gaseous mixture is separated out, and a second plurality of extensions by means of which said component which has been separated out is further cooled.

7. A rectification column as set forth in claim 6 wherein in said portion of said support member located outside said boiling vessel is traversed by said gaseous mixture containing a plurality of components having different separation ranges, at least two groups of extensions secured to said support member for separating out at least two components whereby the components of one separation range are separated out on one of said groups of extensions and the components of another separation range are separated out on another group of extensions.

8. A rectification column as set forth in claim 6 further comprising a third group of extensions for cooling said gaseous mixture, said third group being located between said other two groups of extensions.

9. A rectification column as set forth in claim 6, wherein the groups of extensions are arranged in superposed relationship.

10. A rectification column as set forth in claim 6

wherein at least a certain number of said extensions have different heat resistances.

11. A rectification column as set forth in claim 6 wherein the second part of said heat exchanger is provided with apertured extensions in the form of transverse partitions bounding spaces from the hot side of the heat exchanger to the cold side thereof, said spaces being in communication with one another through said apertures.

12. A rectification column for separating gaseous mixtures comprising a boiling vessel for the fraction having the highest boiling point, a heat exchanger for supplying heat to liquid in said boiling vessel from the gaseous mixture to be fractionated, said heat exchanger having a hollow member, and said heat exchanger being provided with a first part located in said boiling vessel through which heat is supplied to the fraction having the highest boiling point, and a second part located outside of said boiling vessel and in thermal contact with the gaseous mixture to be fractionated, said first and second parts being integral with one another and passing through the bottom of said boiling vessel, said second part of the heat exchanger being provided with a wall spaced apart from said support member, and said sup-

port member being provided with extensions constructed in the form of transverse partitions whereby a plurality of openings remain between said partitions and said wall.

13. A rectification column as set forth in claim 12 wherein said second part of the heat exchanger is constituted by a support member and a wall spaced apart therefrom, said support member being provided with transverse partitions extending to said wall and said partitions being provided with apertures.

14. A rectification column as set forth in claim 12 wherein said second part of the heat exchanger is constituted by a support member and a wall spaced apart therefrom, said support member being provided with transverse partitions extending to said wall and said partitions being provided with non-aligned apertures.
